END SILL FOR RAILWAY CARS

Martin P. Blomberg, Chicago, Ill., assignor to
Pullman-Standard Car Manufacturing Company,
Chicago, Ill., a corporation of Delaware

Application December 24, 1934, Serial No. 758,899

3 Claims. (Cl. 105—421)

This invention relates to end sills for railway cars, particularly that type of car and framing shown in my copending application, Serial No. 752,917, filed November 14, 1934, and the principal objects of the invention are to provide an end sill that is strong, light-weight, and easily cast or otherwise fabricated; that is particularly suitable for use with a car underframe of the type shown in my copending application above identified; that facilitates the running of air lines and cable conduit from one car section to another; and that is exceptionally strong at its mid-section where the greater part of the forces acting on the end sill are applied.

Further and other objects and advantages will become apparent as the disclosure proceeds and the description is read in conjunction with the accompanying drawings, in which

Fig. 1 is a perspective view showing the end framing of the articulated car shown in my copending application above identified;

Fig. 2 is a fragmentary, horizontal, sectional view taken on the line 2—2 of Fig. 1;

Fig. 3 is a perspective view of the lower portion of the end framing, the point of view being within the car;

Fig. 4 is a horizontal, sectional view taken on the line 4—4 of Fig. 6 with fragments being broken away to show the structure below;

Figs. 5, 6, and 7 are sectional views taken on the lines 5—5, 6—6 and 7—7 of Fig. 4.

But this specific illustration and the following specific description are for the purpose of disclosure only, and should not be construed as imposing limitations on the appended claims except as required by the prior art.

Referring first to Fig. 1, in which the end framing of the car described in my copending application, hereinbefore identified, is shown, it will be seen that the underframe includes an end sill, generally designated 10, fabricated side sills 11, a plurality of longitudinal stringers including I-bars 12, J-bars 13, and Z-bars 14, the stringers being supported at intervals throughout their length by transverse cross bearers not shown. Fabricated corner posts 15 and door end posts 16 rise from the end sill and have their upper portions secured to an anti-telescoping plate 17. Built-up top-chords 18 connect the upper ends of the corner posts at opposite ends of the car and a box girder top sill 19 frames into a curved plate 20 which is structurally connected to the tops of the door end post 16. The top chords 18 on opposite sides of the car are joined by arcuate

carlines 21, the latter being covered by roof sheathing 22.

A more detailed description of the car framework may be found in my copending application hereinbefore identified and the remaining part of the disclosure will be confined to the end sill 10 and its appurtenances.

The end sill is preferably an aluminum alloy casting but it may be made of plates welded together into a unitary structure, or fabricated in some other manner. It has a nose portion 23 at the peak of which is a buffer cap 24 flanked by rearwardly recessed ledges 25. The buffer cap is stepped and includes a riser portion 26.

The casting comprises a top web 27, a bottom web 28, a transverse web 29 running the entire width of the casting, a front web 30, and a plurality of longitudinal, vertical webs 31, 32, 33, and 34. The webs 32, 33, and 34 intersect the transverse web 29 and are integral with the front web 30 (see Fig. 4), and the webs 34 which are nearest to the car center line, extend rearwardly beyond the remainder of the webs.

The longitudinal, vertical webs 31, 32, 33, and 34 form with the top and bottom webs 27 and 28 and the transverse web 29 a series of pockets into which the longitudinal stringers 12, 13 and 14 are adapted to enter (as best shown in Fig. 3). The I-bars 12 have their top and bottom flanges, as well as their webs riveted to the end sill castings, the webs 34 being notched out as indicated at 35 to accommodate the flanges of the I-bars and the top and bottom webs 27 and 28 of the end sill casting being extended rearwardly as indicated at 36 in the region of the webs 34.

The J-bars 13 are secured to the vertical webs 33 and the Z-bars 14 to the vertical webs 32, the top flanges of the J-bars being notched out as indicated at 37 to accommodate the web 33, 40 and the Z-bars being notched out as indicated at 38 to accommodate the webs 32.

The ends of the end sill are recessed as shown at 39 to receive the complex corner post construction, and a ledge 40 frames with the side sill 11, as best shown in Fig. 3.

On the under side of the extreme ends of the end sill are jacking blocks 41 and these are equipped with lugs 42 to receive the skirt 43 of the side sill assembly.

On the upper face of the end sill are integrally cast lugs 43 and 44 to which the door end posts 16 are securely attached. The lugs are irregularly shaped due to the fact that the door end posts are of box column construction in order to 55

have maximum strength and in order to provide an air duct 46 which can be used as a part of the ventilating system of the car.

A female center plate 47 is secured by bolts 48 and a key 49 to the under side of the nose portion 23 of the casting 10, and a male center plate 50 carried in a similar manner by the adjacent end sill is adapted to nest with the center plate 47 to form an articulated joint, as best shown in Fig. 6. The latter plate rotates in a truck center plate 51 carried by the truck bolster 52 in any suitable manner.

The female center plate 47 has a peripheral groove 53 adapted to receive a safety cable 54 anchored to lugs 55 integrally formed with the male center plate 50.

The center plates 47 and 50 each have an up-standing dowel 56 which enters an opening 57 in the buffer caps 24 lined with a steel bushing 58. The dowel 56 and key 49 of the center plates serve to relieve the bolts 48 of much of the shear they would otherwise have to take.

The abutting portions of the buffer caps 24 are equipped with wear shoes 59 rounded in a vertical plane.

Access to the bolts 48 is provided through openings 60 in the top web of the casting (see Figs. 1, 4, and 6).

The car bodies are steadied on the articulated joints by side bearings, generally designated 61, each of which includes a rocker 62 pivoted at 63 to a bracket 64 rising from the truck bolster 52, the rocker 61 having at each end a wear plate 65 adapted to engage a similar wear plate 66 which is yieldingly backed by a rubber pad 67 mounted in an inverted cup-shaped projection 68 integral with the end sill casting (see Fig. 5).

The buffer cap 24 is stepped as shown in Fig. 1 and openings 69 are provided in the riser portion 26 to permit the air pipes 70 to pass from one car unit to the adjacent car unit (see Figs. 4 and 6). The necessary flexibility of the pipes in passing from one unit to the other is obtained by providing flexible hose 71 at the crossover.

The electrical conduits are transferred from one car unit to another by jumpers generally designated 72, which emerge from points adjacent to the ends of the end sill of one car unit and enter the abutting end sill adjacent to the car center line (see Fig. 4). The fitting 73 supports the cable as it emerges from the end of the sill, and a fitting 74 supports the cable as it enters the opposite end sill alongside the buffer cap 24. The fitting 74 is secured by bolts 75 to the recessed ledges 25 (see Fig. 7) and the conduits enter the casting through an opening 76 in the rear wall of the recess. Slots 77 are provided in the nose of the casting to afford access to the bolts 75.

The casting is made exceptionally strong throughout its nose portion 23 because the buff

and draft forces are transmitted from one car unit to another through the articulated joints and the buffer caps 24. Accordingly, a pair of closely spaced webs 78 are provided to reinforce the cap 24 and transmit the forces through the end sill to the longitudinal stringers 12, 13, and 14 and the side sills 11. It is for this reason, too, that the webs 34 are extended rearwardly beyond the other vertical webs.

The end sill construction which has been described is exceedingly sturdy and it is framed into the underframe in such a manner that very little bending moment is applied to the sill. Being cast of aluminum alloy, it is of exceptionally light weight and the metal is distributed so that each part serves a particular function in taking the stress.

The reinforced nose portion 23 serves not only to transmit the forces applied to the buffer cap to the longitudinal stringers 12, 13, 14 in a manner which reduces the possibility of fracture to a minimum, but it also provides the necessary room for the fittings 74 so that the cable jumpers 72 may work on a radius and consequently have longer life.

I claim:—

1. An end sill for railway cars comprising a casting having pockets in its rear face for receiving the longitudinal sills of the car underframe, said casting also having a nose portion projecting forwardly beyond the main body of the casting, said nose portion including a stepped buffer cap, the riser portion of which is provided with a pair of openings through which the air line of the car is adapted to pass.

2. An end sill for railway cars comprising a casting having pockets in its rear face for receiving the longitudinal sills of the car underframe, said casting also having a nose portion projecting forwardly beyond the main body of the casting, said nose portion including a buffer cap flanked by rearwardly-recessed shelves, the rear walls of the recessed shelves being provided with openings through which longitudinal cable conduits are adapted to pass.

3. An end sill for railway cars comprising a casting having a top web, a bottom web, said webs having rearward extensions adjacent the central portion of the sill, a vertical web extending from one end of the casting to the other between the front and rear thereof, transversely to said extensions, vertical webs extending parallel with the longitudinal direction of said extensions and forming pockets opening rearwardly, certain of said last-named webs being located between said extensions but spaced therefrom, a nose portion projecting forwardly beyond the main body of the casting and a stepped buffer cap at the peak of said nose portion.

MARTIN P. BLOMBERG. 60
